UNITED STATES PATENT OFFICE.

HAROLD C. COLEGROVE, OF DETROIT, MICHIGAN.

CHANGEABLE SIGN.

1,319,513.

Specification of Letters Patent. Patented Oct. 21, 1919.

Application filed January 22, 1919. Serial No. 272,462.

To all whom it may concern:

Be it known that I, HAROLD C. COLEGROVE, a citizen of the United States, residing at Detroit, in the county of Wayne and State 5 of Michigan, have invented a new and useful Changeable Sign, of which the following is a specification.

This invention relates to changeable signs and has particular reference to changeable signs having frames of sectional construction, such as to permit the size of the sign to be varied.

It is the object of the invention to provide a sign having its frame comprised of tubular 15 sections, adapted to be expeditiously telescopically engaged or disengaged, said sections being slotted to receive the sign plates and also to render the engaging end portions resiliently expandable and contractible so as 20 to facilitate their ready assembly or disassembly.

The provision of means to insure registration of all of the slots of the several sections when the same are assembled to form 25 the frame is a further feature of the invention, the same means preferably serving also to prevent accidental disengagement of the sections.

In attaining these objects the invention 30 contemplates a sectional sign frame formed of tubular units, each having one extremity so reduced in diameter that it will snugly fit within the unreduced end of an adjoining section, the units or sections being slotted 35 from end to end to receive sectional sign plates and having their telescopically engaging portions formed with corresponding peripheral projections and depressions which interengage when the sections are telescopically connected.

A preferred embodiment of the invention is illustrated in the accompanying drawings, wherein,

Figure 1 is a front view of the sign, showing the lower portion of the frame in sections.

Fig. 2 is a perspective view of several sections of the sign frame in disassembled relation.

Fig. 3 is an enlarged view of the sign in cross-section, the section being taken upon line 3—3 of Fig. 1.

In these views the reference character 1 designates a plurality of sign plates, each 55 bearing one or more letters or figures, which are combined to form the desired words or

numbers. Said plates are adapted to be mounted in a sectional frame comprising a plurality of intermediate tubular members 2 and a pair of end tubular members 3. 60 Each of said members is sufficiently reduced in diameter at one end, 4, to fit snugly within the unreduced end of an adjoining frame member. The members 2 are straight and the members 3 approximately U-shaped. 65 Thus while the length of the sign frame may be greatly varied, the height of said frame is maintained constant by the end members 3. It is apparent, however, that the end members might be formed of sections similar to those constituting the top and bottom members of the frame, in case it were desired to provide for variations in the height 70 as well as in the length of the frame.

Each of the members 2 and 3 is slotted 75 from end to end as indicated at 5, the slots being proportioned in width to receive the marginal edges of the plates 1. Furthermore, each of said members has a peripheral 80 teat or punch-prick 6 upon its reduced end portion which is adapted to fit snugly into an indentation 7 formed interiorly in the unreduced end portion of an adjoining section, when said adjoining sections are telescopically engaged. The parts 6 and 7 are 85 so located with reference to the slots 5 that registration of the slots in adjoining sections is established and maintained when said parts are engaged. It is evident also that telescopic engagement of the sections is 90 maintained through the engagement of parts 6 and 7. The slotted construction of the sections permits the same to undergo a slight circumferential expansion when telescopic engagement is being established so that the 95 projection 6 does not prevent establishment of such engagement.

In putting together two adjoining sections of the frame the projection 6 of one may 100 slidably enter the slot 5 of the other while telescopic engagement is being established, and the two sections may be then relatively rotated to introduce said projection 6 into the indentation 7 of the other member.

Obviously by using more or less of the 105 sections 2, the length of the sign frame may be increased or diminished to any desired extent.

What I claim is:

1. A sign comprising a plurality of sign 110 plates, and a frame for said plates consisting of telescopically engaged tubular sec-

- 15 reduced end portion of an adjoining section, said sections being slotted longitudinally to receive marginal portions of the plates, the telescopically engaged portions of the sections being respectively formed with a projection and an indentation receiving said projection, said indentation and projection being located with reference to the slots of said sections to insure registration of said slots when interengaged.
- 16 2. A sign comprising a plurality of sign plates, and a frame for said plates consisting of tubular sections each having an end portion of reduced diameter within the un-
- 20 reduced end portion of an adjoining section, said sections being slotted longitudinally to receive marginal portions of the plates, the telescopically engaged portions of the sections being respectively formed with a projection and an indentation receiving said projection, said indentation and projection being located with reference to the slots of said sections to insure registration of said slots when interengaged.

In testimony whereof I sign this specification.

HAROLD C. COLEGROVE.
